[57] CLAIM

The ornamental design for an adjustable plate holder, as shown and described.

DESCRIPTION

FIG. 1 is a front elevational view of an adjustable plate holder showing my new design;
 FIG. 2 is a rear elevational view of FIG. 1;
 FIG. 3 is a bottom plan view of FIG. 1;
 FIG. 4 is a top plan view of FIG. 1;
 FIG. 5 is a side elevational view taken from the left of FIG. 1, the side opposite being a mirror image thereof;
 FIG. 6 is a reduced perspective view of FIG. 1;
 FIG. 7 is a front elevational view of a second embodiment of the design of FIG. 1;
 FIG. 8 is a rear elevational view of FIG. 7;
 FIG. 9 is a bottom plan view of FIG. 7;
 FIG. 10 is a top plan view of FIG. 7;
 FIG. 11 is a side elevational view taken from the left of FIG. 7, the side opposite being a mirror image thereof;
 FIG. 12 is a reduced perspective view of FIG. 7.
